UNITED STATES PATENT OFFICE

111,469

DESIGN FOR A RAMP FOR THE PROTECTION OF HOSE PIPES

George Allen Bainbridge, Cardiff, Wales

Application November 26, 1937, Serial No. 73,191

Term of patent 14 years

To all whom it may concern:

Be it known that I, George Allen Bainbridge, a subject of the King of Great Britain and residing at the Central Fire Station, Westgate Street, Cardiff, in the county of Glamorgan, Wales, have invented a new, original, and ornamental Design for a Ramp for the Protection of Hose Pipes, of which the following is a specification, reference being had to the accompanying drawing, forming part thereof.

Figure 1 is a perspective plan, whilst,

Figure 2 is a bottom perspective view of a ramp for the protection of hose pipes showing my new design.

I claim:

The ornamental design for a ramp for the protection of hose pipes, substantially as shown.

GEORGE ALLEN BAINBRIDGE.
